UNITED STATES PATENT OFFICE.

WALTER E. HORTON, OF ARLINGTON, AND ABRAHAM CARO, OF DORCHESTER, MASSACHUSETTS, ASSIGNORS TO THE HORTON & HUBBARD MFG. CO., OF EAST SOMERVILLE, MASSACHUSETTS, A CORPORATION OF MASSACHUSETTS.

DESIGN FOR A LOCK.

Application filed December 31, 1928. Serial No. 29,465. Term of patent 7 years.

To all whom it may concern:

Be it known that we, WALTER E. HORTON and ABRAHAM CARO, citizens of the United States, residing at Arlington, county of Middlesex, State of Massachusetts, and Dorchester, county of Suffolk, State of Massachusetts, respectively, have invented a new, original, and ornamental Design for Locks, of which the following is a specification, reference being had to the accompanying drawing, forming part thereof.

Figure 1 is a plan view of a lock, showing our new design.

Figure 2 is an edge view thereof.

We claim:

The ornamental design for a lock, as shown.

ABRAHAM CARO.
WALTER E. HORTON.
